REFRIGERATION SYSTEM

John Lithgow, Leslie K. Jackson, and Kenneth R. Evans, Cleveland, Ohio, assignors to Sears, Roebuck and Co., Chicago, Ill., a corporation of New York

Application August 15, 1939, Serial No. 290,315

9 Claims. (Cl. 62—118)

Our invention relates to a refrigeration system and is especially concerned with an improved rectifier or dehydrator for refrigeration apparatus. More particularly our invention relates to a dehydrator especially adapted for use with an intermittent absorption refrigeration system.

In absorption refrigerators of the intermittently operating type it is essential to provide an extremely efficient dehydrator to separate distilled absorbent (usually water) from the refrigerant in the gases evolved from the still during the generating period. One of the disadvantages of the dehydrators previously provided in machines of this character was the lack of sufficient heat radiating capacity. In some instances where dehydrators of a large heat radiating capacity were provided, these dehydrators occupied a very large space in the refrigerator cabinet, and, as a result, were instrumental in increasing the bulk thereof.

Dehydrators of the character previously provided were also very difficult to fabricate and assemble with the remaining elements of the refrigerator. In many instances very complex bending jigs were necessary for mass production. It was also very difficult to increase the radiating capacity of these dehydrators without a complete redesign of the dehydrator structure.

One of the objects of our invention therefore resides in the provision of a dehydrator characterized by an extremely large heat radiating surface.

Another object of our invention is the provision of a dehydrator which is formed from a multiplicity of similar conduits having a relatively small number of simple bends.

Still another object of our invention is the provision of a dehydrator formed from a plurality of welded conduits, the welds joining the conduits being all located at one end of the dehydrator structure.

A fourth object is the provision of a dehydrator which may be readily increased in size and heat radiating capacity.

A further object is the provision of a dehydrator which is especially adapted to be mounted in a comparatively narrow space in a refrigerator cabinet.

Other objects of our invention will be apparent from the subsequent description and drawing.

Referring to the drawing forming part of this specification and illustrating preferred embodiments of our invention,

Fig. 1 is an elevation of one form of a dehydrator.

Fig. 2 is a modified form of dehydrator according to our invention and

Fig. 3 is a diagrammatic view of an absorption refrigeration system embodying our invention.

Referring first to Figs. 1 and 3, the numeral 10 indicates in general a dehydrator which is adapted to be inserted in a conventional or other intermittent refrigeration system between the generator of the system and a suitable condenser or evaporator. Fig. 3 shows diagrammatically one form of our improved dehydrator inserted in a system substantially of the general type disclosed in Lithgow and Jackson application, Serial No. 214,441, filed June 18, 1938. In this system the generator is indicated at G, the evaporator is indicated by the character E, and the condenser by the character C. A conduit 11 is connected to the generator and serves to carry off the volatilized refrigerant, as for example, ammonia therefrom in admixture with absorbent as for example, water. In most instances the conventional mixture in the generator is a solution of ammonia and water, although it is to be understood that the dehydrator here disclosed is suitable for separating any relatively low boiling refrigerant from the higher boiling absorbent evolved from the generator. The conduit 11 communicates at its lower end with the bottom portion of a trap 12. The trap 12 is provided with an overflow 13 which serves to carry condensed absorbent or water back to the generator of the system. The overflow conduit 13 also determines the height of the liquid in the trap 12.

Leading from the upper portion of the trap 12 is a conduit 14 which communicates with the first of a group of parallel conduits constituting the heat radiating portion of the dehydrator 40 proper. Each of these groups of conduits comprises a down-flow leg successively indicated by the reference numerals 15, 16 and 17, respectively, and an up-flow leg successively indicated by the reference numerals 18, 19 and 20. The 45 last up leg of the series communicates with the condenser and the evaporator of the system. The lower portion of each down-flow conduit is designated by the reference numerals 21, 22 and 23 and communicates by means of a connecting conduit 24 with the trap 12 above the normal liquid level therein as determined by the overflow 13. Each up-flow conduit communicates with its respective down-flow conduit at a point intermediate the outlet and inlet of the down-flow conduit. Thus the up-flow conduit 18 com-

municates with the down-flow conduit 15 at 25; the up-flow conduit 19 communicates with the down-flow conduit 16 at 26; and the up-flow conduit 20 communicates with the down-flow conduit 17 at 27. Preferably each conduit is welded at 25, 26 and 27, and also at its connection with conduit 24, although any other suitable method of joining the conduits for a fluid-tight communication may be used, such as soldering, brazing or by means of a threaded coupling. Each 10 of the vertical reaches of the conduits may be provided with a suitable fin structure (not shown) in order to increase the heat exchange efficiency.

The dehydrator is especially suitable for mounting in a refrigeration cabinet in a narrow flue, as disclosed in the co-pending application Ser. No. 290,314 or it may be positioned at the back of the cabinet exposed to the air in the surrounding room. A dehydrator of the character set forth is especially easy to manufacture. It will be noted particularly that the down-flow conduit 15 is a continuation of the conduit 14, the conduit 16 is a continuation of the conduit 18, and that the conduit 17 and connecting conduit 24 is a continuation of the conduit 19, so that the bending operations are similar and easily performed on conventional bending equipment. It should also be noted that all of the welds or connections between the conduits are located at the lower end of the structure. The size of the dehydrator disclosed may be easily varied by welding an additional conduit to the assembly or by removing the intermediate conduits 16 and 18.

The dehydrator shown in Fig. 2 is quite similar in certain respects to that disclosed in Fig. 1. Similar up and down flow conduits are here provided and indicated by the reference numerals 14a, 15a, 16a, 17a, 18a, 19a and 20a. It will be noted that in the dehydrator disclosed in Fig. 2, there is no connecting conduit corresponding to the conduit 24 of Fig. 1. Instead the lower end 22a and 23a of each down-flow conduit communicates with each preceding down-flow conduit adjacent the lower end thereof, as at points 28 and 29. This modification therefore eliminates the additional bending of the last down-flow conduit 17 to form the connecting conduit 24 and substitutes the two additional welds at 28 and 29.

The operation of the dehydrator shown in Fig. 1, which is similar to that shown in Fig. 2, is as follows:

A mixture of high boiling absorbent and low boiling refrigerant enters the trap 12 through the conduit 11 where a preliminary separation of refrigerant from absorbent takes place, the absorbent flowing back to the still of the system through the overflow conduit 13. The mixture of refrigerant and absorbent vapors flow up the conduit 14 and successively through the conduits 15, 18, 16, 19, 17 and 20. A portion of the higher boiling absorbent is separated by condensation from the refrigerant in each of these conduits and the absorbent flows down the conduits 21, 22 and 23 to the connecting conduit 24 and back to the trap 12. From the trap 12 the water flows back to the still of the system through the overflow 13. The refrigerant gas substantially free from absorbent flows out of the upper end of the last up-flow conduit 20 to the condenser and evaporator of the system.

The operation of the embodiment of Fig. 2 is generally similar to that of Fig. 1.

The operation of the system shown in Fig. 3, is fully described in application Serial No. 214,441. The character D represents a drain conduit leading from a sump of the evaporator 5 E to the trap 12, this drain conduit having an enlarged section S therein and serving to draw off from the evaporator any small quantity of absorbent liquid which may escape condensation in the dehydrator 10. Exhausted refrigerant gas is returned from the evaporator to the generator-absorber G by means of the return conduit R.

Various modifications and changes coming within the spirit of our invention may suggest themselves to those skilled in the art, and, hence, we do not wish to be limited to the specific forms shown or uses mentioned except to the extent indicated in the appended claims.

We claim:

1. A refrigeration system including a generator, a condenser, and a dehydrator disposed in operative relation between said generator and said condenser, the dehydrator comprising a series of originally separate integral tubes connected together, each tube consisting of an up leg and a down leg, each up leg being connected to the down leg of the preceding tube above the lowermost portion of the latter, whereby a continuous unobstructed gas passage is provided, and a liquid return conduit formed by a portion of at least one of said tubes.

2. A refrigeration system including a generator, a condenser, and a dehydrator disposed in operative relation between said generator and said condenser, the dehydrator comprising a series of originally separate integral tubes connected together, each tube consisting of an up leg and a down leg, each up leg being connected to the down leg of the preceding tube above the lowermost portion of the latter, whereby a continuous unobstructed gas passage is provided, each down leg being connected to the down-leg of the preceding tube to provide a liquid return passage.

3. A refrigeration system including a generator, a condenser, and a dehydrator disposed in operative relation between said generator and said condenser, the dehydrator comprising a series of originally separate integral tubes connected together, each tube consisting of an up leg and a down leg, each up leg being connected to the down leg of the preceding tube above the lowermost portion of the latter, whereby a continuous unobstructed gas passage is provided, and a liquid return conduit formed by a portion of at least one of said tubes, all of said tubes lying in substantially the same plane.

4. A refrigeration system including a generator, a condenser, and a dehydrator disposed in operative relation between said generator and said condenser, the dehydrator comprising a series of originally separate integral and similar tubes connected together, each tube consisting of an up leg and a down leg, each up leg being connected to the down leg of the preceding tube above the lowermost portion of the latter, whereby a continuous unobstructed gas passage is provided, and a liquid return conduit formed by a portion of at least one of said tubes.

5. A refrigeration system including a generator, a condenser, and a dehydrator disposed in operative relation between said generator and said condenser, the dehydrator comprising a plurality of substantially similar generally U-shaped integral tubes, each tube having a relatively long leg and a relatively short leg, the short leg of

each tube being connected to the long leg of the adjacent tube at a point between the top and bottom of the long leg, and a liquid return conduit connecting the lower extremities of the long legs, said conduit being formed entirely of a portion of at least one of said tubes.

6. A refrigeration system including a generator, a condenser, and a dehydrator disposed in operative relation between said generator and said condenser, the dehydrator comprising a plurality of originally separate substantially similar generally U-shaped integral tubes, each tube having a relatively long leg and a relatively short leg, the short leg of each tube being connected to the long leg of the adjacent tube at a point between the top and bottom of the long leg, a liquid return conduit connecting the lower extremities of the long legs, said conduits being formed entirely of a portion of at least one of said tubes, means for conducting mixed absorbent and refrigerant vapors from a still to the dehydrator, a trap disposed between said conducting means and the first up leg, and means for conducting vapor from the last down leg to an evaporator, said liquid return conduit discharging into said trap.

7. A refrigeration system including a generator, a condenser, and a dehydrator disposed in operative relation between said generator and said condenser, the dehydrator comprising a plu-

rality of originally separate substantially similar generally U-shaped integral tubes, each tube having a relatively short up leg and a relatively long down leg, the legs of at least certain of said tubes terminating in laterally extending portions connected to the preceding down leg.

8. A refrigeration system including a generator, a condenser, and a dehydrator disposed in operative relation between said generator and said condenser, the dehydrator comprising a plurality of originally separate substantially similar generally U-shaped integral tubes, each tube having a relatively short up leg and a relatively long down leg, the last down leg being bent laterally to form a liquid return conduit, each up leg being connected to the preceding down leg substantially above the lowermost portion thereof and every other down leg but the last one discharging into said laterally bent portion.

20 9. A refrigeration system including a generator, a condenser, and a dehydrator disposed in operative relation between said generator and said condenser, the dehydrator comprising a plurality of originally separate substantially similar generally U-shaped integral tubes, said tubes being connected only to one another to provide vapor passage and liquid return.
